UNITED STATES PATENT OFFICE.

WILLIAM A. GRAHAM, OF CARLISLE, PENNSYLVANIA.

OSCILLATING STEAM-ENGINE.

SPECIFICATION forming part of Letters Patent No. 413,506, dated October 22, 1889.

Application filed April 16, 1889.

Serial No. 307,509. (No model.)

To all whom it may concern:

Be it known that I, WILLIAM A. GRAHAM, of Carlisle, in the county of Cumberland and State of Pennsylvania, have invented certain new and useful Improvements in Oscillating Steam-Engines; and I do hereby declare the following to be a full, clear, and exact description of the invention, such as will enable others skilled in the art to which it appertains to make and use the same.

My invention relates to an improvement in steam-engines, the object being to provide an engine which shall be compact in form, powerful and steady in action, composed of few parts, simple in construction, of great efficiency in its operation, and of comparatively small initial cost in its manufacture.

With these ends in view my invention consists, first, in an oscillating steam-engine comprising an oscillating cylinder, a valve-chest contiguous thereto, and a tapering balanced valve, with connections for oscillating said valve simultaneously with but in an opposite direction from the motions of the chest in which the valve is fitted.

The invention further consists in an oscillating engine having an oscillating cylinder supported on hollow trunnions, and live-steam and exhaust pipes located loosely within the trunnions in such a manner that a steam-tight joint is automatically formed by the impact of the steam upon the pipes.

The invention further consists in an oscillating steam-engine provided with a suitable cylinder, a cylindrical valve-chest, a tapering valve supported in tapering bearings within this valve-chest, said valve having ports therein, and means for admitting steam to balance pressure, and ports in the cylinder for the passage of live and exhaust steam.

The invention still further consists in an oscillating cylinder employed in combination with a cylindrical valve-chest, a tapering oscillating valve, and means for automatically moving the valve within the valve-chest, but in a contrary direction, and in so doing regulating the throw of the valve to admit and discharge more or less steam.

The invention still further consists in certain features of construction for compensating for wearing of the valve or the interior of the valve-chest, for preventing the valve

from sticking, and for lubricating the various parts having frictional contact, and in other novel features of construction and combinations of parts, as will be hereinafter fully described, and pointed out in the claims.

In the accompanying drawings, Figure 1 is a side elevation. Fig. 2 is a plan view, partly in section, on line *xx* of Fig. 1. Fig. 3 is a section on the line *yy* of Fig. 2. Fig. 4 is a section. Fig. 5 is a modified form of device for regulating the throw of the valve.

A represents the cast-iron bed or frame on which the various parts of the engine are supported. The casting may be of different shapes; but the preferred form is L-shaped. This frame is provided with suitable pillow-blocks which furnish bearings for the trunnions.

B represents the cylinder, having the hollow trunnions *11* supported in pillow-blocks *22*, whereon the cylinder oscillates, in the accustomed manner of engines of this character. Boxes *33* are held down by bolts or other means over the trunnions to keep them in their bearings, and on these boxes *33* oil-cups *4* are located for supporting a lubricator to the trunnions.

Piston *C* is fitted to reciprocate in the cylinder, and this piston may have the usual packing-ring *5* to insure a steam-tight fit within its walls. The piston-rod *6* extends from the piston forward through the adjustable packing-rings *6a* on the end of the cylinder to the fly-wheel *7*, where it is connected directly by means of the strap-head *8* to one of the spokes of the wheel. The fly-wheel is provided with an enlarged or webbed spoke *9*, and the strap-head is connected with a wrist *10*, projecting from this webbed spoke. The rotary shaft *12*, on one end of which this fly-wheel is held, is supported in the pillow-block *13*, and to the opposite end of this shaft a band-wheel *14* is affixed. A cap *15* is fastened over this shaft, and an oil-box *16* therein supplies a lubricator for the shaft.

Returning to the cylinder *B*, it will be observed that a cylindrical valve-chest *17* is located over the cylinder, which preferably extends at right angles to it. The central portion of the interior of this chest is lined with brass or Babbitt metal *18*, which constitutes a seat for the valve. This lining or seat

tapers slightly from one end to the other and is adapted to receive the tapering valve 19, which is neatly fitted to the lining to turn smoothly therein and at the same time prevent the leakage of steam between it and the lining. The valve consists of a hollow tapering drum made solid through the middle, where it joins the axle 20, and having recessed or excavated ends. The smaller end 21 of this valve is beveled, and the larger end 22 is square or enlarged to furnish an abutment for the pressure of steam from the live-steam duct. Two ports 23 23 are formed in the valve extending from the inside to the exterior, and between these ports an exhaust-port 24 is cut in the valve. These ports are adapted to register with steam-ducts 25 25, which lead to the opposite ends of the cylinder and to the exhaust-duct 26, and control the passage of steam in these ducts. A live-steam duct 27 leads from one of the trunnions 1 to the valve-chest, and the exhaust-steam duct 26 leads in the opposite direction into the other trunnion 1. Diametrically opposite the exhaust-duct 26 there is formed in the valve a chamber 26^a, and ports leading to this recess supply steam for balancing the valve and equalizing the pressure. When the heads 28 29 are screwed onto the ends of the chest, the latter is steam-tight, and steam upon entering through live-steam ducts 27 is made to pass alternately into one or the other of the ducts 25, accordingly as the ports of the valve 19 register with one or the other of these ducts. The steam is fed and discharged through similar pipes 19^a 19^a. These pipes extend loosely through screw-plugs 19^b in the trunnions 1 1, where they are held by said plugs. In order to form a steam-tight joint, the inner ends of these screw-plugs are ground off perfectly true and smooth, and the inner ends of the pipes 19^a are furnished with a collar 19^c, similarly ground on the side adjacent to the plug, so that the two fit each other perfectly and are held tightly together by the back-pressure of steam against the ends of the pipes, thus forming a steam-tight joint. The valve-rod 20 is supported in the head 28 of the valve-chest, from which it projects out a short distance through the adjustable packing-box 31. The valve-rod 20 terminates at the opposite end a short distance from the head 29, and a set-screw 33 in the center of this head is adapted to be turned slightly to bear on the end of the valve-rod to guard against the valve sticking, which otherwise might result, owing to the tapering form of the valve, and due to the fact that the greatest pressure of steam is always on the opposite end, where the tendency is to force the valve in the direction of its taper.

An upright support 34 is located at one end of the valve-chest, and preferably secured to the pillow-block 2 adjacent thereto. A stem 35 extends loosely into this support, where it is fitted to reciprocate up and down with the motion of the engine. Slide-block 36 is af-

fixed to this stem, and this block is guided in its motions in the elongated slot 37. A cylindrical bolt 38 fits in this slide-block, and is intended to rock slightly with the motion of the engine. Sleeve 39, with a cylindrical bore, is affixed to the inner end of this bolt, and an arm 40, of corresponding size and shape with the bore of said sleeve, projects from the axle 20 of the valve, to which it is held fast by a set-screw and pin through the sleeve 39, where the two have sliding contact with each other. Thus the reciprocations of the stem 35 regulate the throw of the valve, and to control the speed of the engine it is important that some mechanism should be employed for automatically varying the length of reciprocations of the stem, for, as will be observed, when the stem is depressed to its utmost, the throw of the valve is most restricted, and when the stem is elevated to its utmost the throw of the valve is the greatest, and when the stem is at different elevations between these two extremes the throw of the valve is correspondingly changed.

The ball-governor 41 is adopted as a practical means for changing the valve, though it should be understood that I do not confine myself to the use of any particular form of governor, as many other varieties would be equally as effective as this one; and, indeed, as will appear from the modification to be presently described, a governor is not absolutely necessary, as other devices might be used; but the governor employed is supported on a rotary shaft 43, and the latter is driven by bevel gear-wheels 44 45, and these wheels are driven by a belt extending from pulley 47 on the main shaft 12 to pulley 48 on the small shaft 49, which carries gear-wheel 45. From the governor a lever 50, fulcrumed on arm 51, extends across to the stem 35, and here the two are loosely connected with each other, so that the faster the governor is driven the farther outward the balls extend, due to the centrifugal force and the higher the connected end of lever 50 is raised. This results in depressing the opposite end of the lever, and, as previously explained, the stem is depressed and the throw of the valve is decreased, so that less steam is taken. This retards the motion of the engine and the balls fall and the contrary effect is felt on the valve, and consequently more steam is taken. Thus the speed is always regulated automatically.

The modification is merely adopted as being most convenient for very small engines—as, for instance, a one or one and a half horse-power. It consists in substituting for the plain stem 35, above described, a screw-threaded stem with a handle 52 on the end, by which it is turned backward or forward, and in dispensing with the governor entirely and its connected mechanism. Otherwise the parts are precisely alike and operate as described.

It is evident that slight changes might be resorted to in the form and arrangement of the several parts described without departing

from the spirit and scope of my invention, and hence I do not wish to limit myself to the particular construction herein set forth; but,

Having fully described my invention, what 5 I claim as new, and desire to secure by Letters Patent, is—

1. In an oscillating steam-engine, the combination, with an oscillating cylinder and valve-chest, the said parts having communicating ducts, whereby steam is admitted to and exhausted from the opposite ends of the cylinder, of a tapering valve fitted to the walls of the valve-chest, said valve having ports therein for directing the passage of steam, a 10 steam-balancing chamber between the valve and its seat, a stationary device, and sliding connections between the stationary device and valve, whereby the throw of the latter is regulated by the oscillation of the cylinder, substantially as set forth.

2. In an oscillating steam-engine, the combination, with an oscillating cylinder mounted on hollow trunnions, and a valve-chest integral with the cylinder, the said parts having 15 communicating ducts, whereby steam is admitted to and exhausted from the opposite ends of the cylinder, and also ducts leading from the latter into the trunnions for the live and exhaust steam, of a tapering valve fitted 20 to the walls of the valve-chest, said valve having ports therein for directing the passage of steam, a steam-balancing chamber between the valve and its seat, a stationary device, and sliding connections between the stationary device and valve, whereby the throw of the lat- 25

ter is regulated by the oscillations of the cylinder, substantially as set forth.

3. In an oscillating steam-engine, the combination, with an oscillating cylinder, a valve-chest, and valve, of reciprocating stem and 40 means for connecting said stem loosely with the valve, whereby motion of the valve and engine is regulated, substantially as set forth.

4. In an oscillating steam-engine, the combination, with an oscillating steam-cylinder, a 45 valve-chest, and valve, of a slotted standard, a reciprocating stem, a slide-block, said block and the valve having sliding jointed connection with each other, and means for automatically raising and lowering the stem, whereby 50 the throw of the valve and the motion of the engine are regulated, substantially as set forth.

5. In an oscillating steam-engine, the combination, with a frame, pillow-blocks, an oscillating cylinder supported on said blocks, a 55 valve-chest, valve, piston, piston-rod, fly-wheel, rotary drive-shaft, and pulleys, of a standard secured to the frame, a slide-block and reciprocating stem, said block having sliding connection with the valve, a governor for operating the stem, and a belt for operating the governor from the drive-shaft, substantially 60 as set forth.

In testimony whereof I have signed this specification in the presence of two subscribing witnesses.

WILLIAM A. GRAHAM.
